United States Patent Office

Des. 186,300

Patented Oct. 6, 1959

186,300

COMPOSITION FLOOR COVERING OR THE LIKE

Beatrice Edesess, Brookline, Mass., assignor to American Biltrite Rubber Co., Inc., Chelsea, Mass., a corporation of Delaware

Application September 12, 1958, Serial No. 52,617

Term of patent 14 years

(Cl. D92—17)

Fig. 1

Fig. 2

Fig. 1 is a plan view of a composition floor covering showing my new design on a reduced scale. The arrows on the figure indicate a design unit which is repeated in regular succession.

Fig. 2 is a view on a full size scale showing a portion of the design.

I claim:

The ornamental design for composition floor covering or the like, substantially as shown and described.
